Inventor:

UNITED STATES PATENT OFFICE.

ALVAN G. CLARK, OF CAMBRIDGEPORT, MASSACHUSETTS.

PHOTOGRAPHIC SHUTTER.

SPECIFICATION forming part of Letters Patent No. 341,130, dated May 4, 1886.

Application filed December 12, 1885. Serial No. 185,430. (No model.)

To all whom it may concern:

Be it known that I, ALVAN G. CLARK, of Cambridgeport, in the State of Massachusetts, have invented a new and useful Improvement 5 in Photographic Shutters, of which the following is a specification.

My invention relates to shutters for use in instantaneous photography.

The object of my invention is to provide a 10 photographic shutter, compact, convenient, and strong, which can be adjusted to various rates of speed, and can act with great rapidity with the minimum of jar to the camera.

My invention consists, first, in the use, for a 15 photographic shutter, of a receptacle which by itself serves as a double exposure, as herein shown and described, in connection with side pieces serves as a permanent double diaphragm or stop having an opening at each of two opposite points, and of a rotating double cut-off, 20 inclosed within said double diaphragm, having an opening at each of two opposite points corresponding to the openings of the inclosing diaphragm, in order that the four openings 25 may come in line, when the cut-off is rotated, to expose the sensitive plate to the rays of light from the object photographed, and that the rays of light from the object photographed 30 may be shut out by this double cut-off, whereby the exposure is made substantially twice as rapidly as an exposure made with a single cut-off having the same rate of speed; or, in other words, a rapid exposure to be made in a given 35 time can be made in such time with this double diaphragm and double cut-off by the expenditure of substantially one-half the force required to make the exposure in the same time with a single diaphragm and single cut-off—that is, a diaphragm and cut-off, each requiring and having but one opening—and the 40 force exerted being less the jar to the camera is correspondingly less.

As herein shown and described, the shutter and operating-spring are placed within the 45 lens-tube and connected with it, and the mechanism for controlling the same is placed without the lens-tube and connected with it. The shutter and its operating mechanism may be distinct from the lens-tube, and be made to fit 50 upon or into the lens-tube when in use; and, as herein shown and described, the diaphragm and inclosed cut-off are hollow cylinders, it is

evident that the same result could be attained without departing from my invention by the use of a similar permanent diaphragm inclosed 55 within, instead of inclosing, a rotating cut-off, provided the passage of light around the inclosing cut-off be prevented; and it is further evident that the two openings of the inclosed cut-off or the inclosed diaphragm, as the case 60 may be, might be formed by means of an opening passing through an otherwise solid inclosed cut-off or diaphragm between points of the same corresponding to the positions of the two openings of the hollow inclosed cut-off or 65 diaphragm without departing from my invention. It is further evident that the same result, to a modified degree, could be attained without departing from my invention, by the use of this double cut-off with a single dia- 70 phragm—that is, a diaphragm requiring and having but one opening—as shown in Figs. 7 and 8.

In the drawings, Figure 1 is an inverted plan of my invention, the shutter placed within 75 the lens-tube and in position to be operated to take a picture, the diaphragm-openings closed by the cut-off. Fig. 2 is a sectional elevation of Fig. 1 on the line *x x*. Fig. 3 is a partial sectional plan of the lens-tube, shutter, 80 and side pieces at positions of the same indicated by the line *y y* in Fig. 2. Fig. 4 is a partial view of Fig. 3, except that here the diaphragm and cut-off openings are shown at the instant they are in line in making an exposure. Fig. 5 is the same as Fig. 4, except 85 that here the diaphragm and cut-off openings are shown at the instant they open to admit the central rays of light. Fig. 6 is the same as Fig. 4, except that here the diaphragm and 90 cut-off openings are shown at the instant they close to shut out the central rays of light. Fig. 7 is the same as Fig. 4, except that here the diaphragm-opening is shown as single—that is, requiring and having but one opening. 95 Fig. 8 is the same as Fig. 7, except that here the diaphragm-opening is shown closed by the cut-off.

The broken lines passing through Figs. 3, 4, 5, 6, 7, and 8 indicate the central lines of 100 light from the object photographed.

The movable hook shown in broken lines in Fig. 1 is to hold the lock *K* when it is desired to have the openings in line, as shown in Fig.

4, for the purpose of focusing or for giving a time-exposure.

T is the lens-tube; F, the receptacle serving in connection with the side pieces, W, as the permanent diaphragm or stop; I, a threaded neck, within which the screw-cap B is worked to regulate the spiral spring S. The spring S is attached to the cap B at S', and coiled around the shaft R, and attached to the plate P of the cut-off C at S'. The shaft R is free to rotate in the cap B, and is fixed to the plate P. The shaft R', attached to the plate P' of the cut-off, passes through the cap B', free to rotate therein, and is rigidly connected with the lock K. The lock K, when the shutter is in position to be operated, is held by the tension of the spring S against the spring piston-rod catch O. When the catch O is removed from contact with the lock K, by means of air sent from an air-bulb through the rubber tube U, as shown in the drawings, or otherwise removed, the lock K being released, the spring S causes the cut-off C to rotate, and the openings D D' of the cut-off to pass the openings E E' of the receptacle F, as shown, and thereby open and close the diaphragm-openings, and admit the light from the object photographed to the sensitive plate

and shut out the same, the lock K flying around and being caught and held by the spring-
catch V.

I claim—

1. A photographic-camera shutter consisting of a double exposer provided with apertures in its opposite sides and a cylinder provided with corresponding apertures in its opposite sides, and adapted to revolve within said exposer, whereby by the continuous revolution of said cylinder the several apertures may be brought into line and out of line with each other, substantially as described, for the purpose specified. 35

2. A photographic-camera shutter consisting of an exposer provided with an aperture and a cylinder provided with apertures corresponding to the aperture of the exposer, and adapted to revolve, whereby by the continuous revolution of said cylinder the several apertures may be brought into line and out of line, substantially as described, for the purpose specified. 45
